Primary Examiner—Louis S. Zarfas*Assistant Examiner*—Frank Martinez*Attorney, Agent, or Firm*—Brumbaugh, Graves, Donohue & Raymond[57] CLAIM

The ornamental design for a folding sweep sport fan, as shown and described.

DESCRIPTION

FIG. 1 is a front view of my new design for a folding sweep sport fan in closed, folded, position;

FIG. 2 is a side view of the sweep sport fan in an open, unfolded position;

FIG. 3 is a top view of the sweep sport fan in an open, unfolded position;

FIG. 4 is a bottom view of the sweep sport fan in an open, unfolded position; and,

FIG. 5 is a front view of the folding sweep sport fan, showing my new design.

The folding sweep fan may be used by a sports fan to indicate a "sweep" in a sporting event.
